UNITED STATES PATENT OFFICE.

WILLIAM GEORGE WEBB, OF BALTIMORE, MARYLAND, ASSIGNOR TO
THOMAS ARMSTRONG, OF SAME PLACE.

DESIGN FOR A CAKE OR BAR OF SOAP.

SPECIFICATION forming part of Design No. 24,506, dated July 30, 1895.

Application filed June 18, 1895. Serial No. 553,234. Term of patent 14 years.

To all whom it may concern:

Be it known that I, WILLIAM GEORGE WEBB, a citizen of the United States, residing at Baltimore, in the State of Maryland, have invented and produced a new and original Design for Cakes or Bars of Soap; and I do hereby declare the following to be a full, clear, and exact description of the same, reference being had to the accompanying drawings, forming a part thereof.

My invention relates to a new design for bars or cakes of soap, and its leading feature consists of the cake or bar having parallel sides and formed with a series of arched surfaces on its sides, so as to impart to the cake or bar the appearance of a cluster of solid columns extending parallel with each other.

Figure 1 of the accompanying drawings represents a perspective view of the bar or cake, and Fig. 2 a cross-section through the same.

In the drawings, the numeral 1 designates the bar or cake, which has its sides formed

of a series of arched or curved surfaces 2, which, as illustrated, extend parallel with each other and lengthwise of the bar or cake, so that when viewed together in side elevation the whole presents the appearance of a cluster of solid parallel columns constituting a bar or cake of substantially uniform dimensions from end to end. I have illustrated the arches as describing curved surfaces or segments of circles, and have shown three arched surfaces on one side and three on the opposite side of the cake or bar; but it is obvious that changes can be made therein and the essential features of the design still be retained.

I claim—

The design for a bar or cake of soap shown and described.

In testimony whereof I affix my signature in presence of two witnesses.

WILLIAM GEORGE WEBB.
